UNITED STATES PATENT OFFICE.

CLARENCE H. HUNSMERGER, OF NORTH TONAWANDA, NEW YORK.

WIRE GUARD FOR ELECTRIC LAMPS.

1,044,785.

Specification of Letters Patent.

Patented Nov. 19, 1912.

Application filed February 9, 1911, Serial No. 607,585. Renewed July 25, 1912. Serial No. 711,573.

To all whom it may concern:

Be it known that I, CLARENCE H. HUNSMERGER, a citizen of the United States, residing at North Tonawanda, in the county 5 of Niagara and State of New York, have invented new and useful Improvements in Wire Guards for Electric Lamps, of which the following is a specification.

This invention relates to a wire guard for 10 inclosing electric light bulbs and other similar fragile articles, and primarily to the means for detachably fastening the wire guard to the bulb or other article.

The object of the invention is to produce 15 a strong, durable and comparatively cheap device of this character, which may be very readily attached to and detached from the electric light bulb or other article, and which when in place, surrounds and protects 20 said bulb or other article from injury.

The invention also relates to certain details of construction of the wire guard and the locking means therefor, which will be hereinafter described and claimed, reference being had to the accompanying drawings in which,

Figure 1 is a perspective view of the wire guard attached to and inclosing an incandescent electric light bulb and a screw socket for said bulb, and a portion of the covered electric conducting wire also being shown. Fig. 2 is a detached top plan view of the wire guard. Fig. 3 is a section through the upper ring to illustrate one of 35 the members of the clasp or lock in side elevation.

In referring to the drawing in detail, like numerals designate like parts.

The improved wire guard consists of an 40 upper circular end ring 1, a plurality of ribs 2 having their upper ends bent around the wire ring 1, and a spirally wound wire 3 which is fastened at its upper end to the upper circular ring 1 and winds spirally 45 downward therefrom, being connected at its contact points by solder or other suitable means to the ribs 2. The ribs 2 have their upper ends attached at equal intervals around the circular upper ring 1, and extend 50 downwardly therefrom, with their lower ends curving inwardly into contact at the point 4.

This improved guard is adapted to loosely surround and inclose an electric light bulb or similar fragile article, and thereby protect it from injury.

Referring to Fig. 1, a conventional form of electric light bulb 5 is shown therein, which is provided with a supporting socket 6 to which said bulb is detachably attached. 60 The socket 6 is connected to the end of a covered electric wire 7 in the usual well known manner.

It will be noted that the improved guard is entirely out of contact with the bulb, 65 means being provided for clasping or locking the wire guard to the socket.

The device for detachably fastening the wire guard to the lamp socket consists of two opposed members which are loosely secured at one end to one side of the ring 1, and extend across to the opposite side of the ring, being sprung or snapped into interlocking engagement at said opposite end to firmly clasp or embrace the lamp socket 75 between them. One of the members of the locking device has an eye-portion 8 at one end which loosely encircles the ring 1, and a return bent portion 9 at its opposite end which fits loosely around the ring 1 on the 80 side opposite the eye-portion 8, as shown in Fig. 3, and an intermediate curved portion 10 which fits partially around the lamp socket when in clasping position, relatively to the same. The other member of the device has a similar eye-portion 11 at one end, which also loosely encircles the ring 1, a laterally bent or hook portion 12 at the opposite end which is adapted to be sprung or snapped upon the end portion 9 of the 90 first-mentioned member, and an intermediate curved portion 13 which curves oppositely to the curved portion 10 of the first-mentioned member, and is adapted to fit partially around the lamp socket opposite 95 said portion 10.

The members of this locking device are preferably made of suitable spring wire.

The upper end of the spiral wire 3 is looped around the upper ring 1, forming a 100 circular enlargement or shoulder 14 around the same, which is located fairly close to the eye 15 of one of the ribs 2, as shown in Fig. 2.

The eyes 8 and 11 of the two members loosely encircle the ring 1, and are located on said ring between the shoulders 14 and 15, and are limited in their circumferential movement on said ring 1 by the said shoulders 14 and 15, as shown in Figs. 1 and 2.

The bent or hook portion 12 at one end of one of the members, is not only bent laterally to form a hook, as previously described, but it is also bent downward and then back, as shown at 16 to form a return bend.

The object of this construction is not only to lock the two members together in their clasping position, but also to provide a double lock between the parts of which the ring loosely fits to lock the members to the ring 1 against vertical movement. This will 20 be easily understood by referring to Fig. 1.

To center the wire guard with respect to the incandescent light bulb, a plurality of diagonally extending wires 17 are fastened at their upper ends to the ring 1, at equal 25 intervals around the circumference of said ring and extending diagonally downward toward each other, gradually converging until they reach the center point 4 at the lower end of the guard to which they are fastened, as shown in Fig. 1. These wires are made 30 of light spring metal and are straight, and are adapted to contact with the surface of the light bulb and thereby center the guard with respect to the bulb, and also to support 35 said bulb within the guard with a yielding or spring tension.

The main advantages of this improved guard reside in the novel means for detachably fastening the same to the socket of the 40 lamp, the strong, simple and cheap construction of the same, and the means for centering and supporting the guard with respect to the lamp bulb.

I claim:

45 1. A wire guard for lamp bulbs consisting of a wire body adapted to loosely inclose a lamp bulb and having an end ring and a multi-member locking device adapted to be sprung or snapped about the socket of the lamp bulb and having those portions of its members at one end thereof loosely attached to one side of the end ring and the opposite end portions of said members being adapted to be sprung into interlocking engagement with each other and one of said members being also adapted to be locked to the opposite side of the end ring against vertical movement.

60 2. A wire guard for lamp bulbs consisting of a wire body adapted to inclose a lamp bulb and having an end ring and a locking device attached to the end ring of the wire body and adapted to be sprung in clasping position about the socket of the lamp bulb,

said locking device consisting of two members, each having an eye at one end loosely encircling the end ring at one side thereof, a return bend portion at the opposite end adapted to be sprung into locking engagement with the bent portion of the other member and around the end ring, and oppositely curved intermediate portions between which the socket of the lamp bulb is clamped.

3. A wire guard for lamp bulbs consisting of an end ring, a series of inclosing wires extending from said end ring, and a locking device for detachably securing said guard to the socket of a lamp bulb consisting of two opposed members loosely secured 80 at one end to one side of the end ring and extending across to the opposite side of said ring, and the opposite ends of said members being adapted to be sprung into interlocking engagement with each other and also 85 with the end ring.

4. A wire guard for lamp bulbs consisting of a wire body adapted to loosely inclose a lamp bulb and having an end ring and a multi-member locking device for detachably securing said guard to the socket of a lamp bulb and consisting of two opposed members loosely secured at one end to one side of the end ring and extending across to the opposite side of said ring; one 95 of said members having a laterally bent hook portion and another of said members also having a laterally bent hook portion which is additionally bent downward and backward to form a return bend and provide 100 a double hook between the parts of which the end ring loosely fits to lock the said members against vertical movement relatively to the end ring and the hook portions of said members being adapted to be sprung 105 together to clamp the guard upon a lamp bulb.

5. A wire guard for lamp bulbs consisting of an upper circular ring, a series of inclosing wires depending from said upper 110 circular ring, and a multi-member locking device for detachably securing said guard to the socket of a lamp bulb, each member of said locking device having an eye at one end loosely encircling the upper ring, and a bent 115 portion at the opposite end adapted to be sprung into locking position with respect to the bent portion of the other member and one of said members also having an additional bent portion adapted to hook around 120 the upper ring to prevent vertical displacement; said members being adapted to clamp the lamp socket between them.

6. A wire guard for lamp bulbs consisting of an upper circular ring, a series of 125 ribs depending from said upper circular ring and connected together at their lower ends, a spiral wire having its upper end fas-

tened to the said circular ring, said spiral wire winding spirally around and being fastened at intervals to the ribs, and also having its lower end fastened to the lower 5 ends of the ribs, and a locking device attached to the upper circular ring and consisting of two members which are loosely

fastened to the ring at one side thereof and in proximity to each other and are adapted to be spring-locked together.

CLARENCE H. HUNSMERGER.
